HOSPITAL OR INVALID BED

Albert L. Hurst, Winston-Salem, N. C.

Application September 12, 1936, Serial No. 100,523

1 Claim. (Cl. 5—90)

My invention relates to improvements in hospitals or invalid beds.

An important object of the invention is to provide a bed of the above mentioned character, which will permit the use of a bed pan or the like, with the minimum inconvenience to the patient and the minimum work on the part of the nurse or operator.

A further object of the invention is to provide an attachment which may be applied to the ordinary or standard hospital bed without materially altering the construction of the same, for producing a bed embodying the invention.

Other objects and advantages of the invention will be apparent during the course of the following description.

In the accompanying drawings forming a part of this application and in which like numerals are employed to designate like parts throughout the same,

Figure 1 is a perspective view of a hospital bed embodying my invention,

Figure 2 is a plan view of the same,

Figure 3 is a side elevation of the same,

Figure 4 is a transverse section taken on line 4—4 of Figure 3,

Figure 5 is a longitudinal section taken on line 5—5 of Figure 4, and,

Figure 6 is an exploded perspective view of the slide bracket and associated elements.

In the drawings wherein for the purpose of illustration is shown a preferred embodiment of my invention, a hospital bed is shown comprising a head 10, foot 11, and side rails 12, connecting the same. The bed further comprises a spring bottom including a frame 13, to which is attached a spring mattress or bottom 14, including links 15, having hooks 16 at their ends. These links are arranged in transverse and horizontal sets and are connected by coupling elements 17, receiving the hooks 16 therein. The spring bottom or mattress may be angularly adjusted, so that the patient may be supported at different angular positions, as is well known in hospital beds, and for this purpose the spring bottom is formed in a head section 18, an intermediate section 19, and a foot section 20. The foregoing is the construction of the conventional hospital or invalid bed. My invention embodies an adjustable support which is bodily suspended from the intermediate section of the spring bottom. This adjustable support comprises a casing 21, including an upper rectangular frame 22, preferably formed of angle iron, and a lower rectangular frame 23, preferably formed of angle iron. These frames

are rigidly connected by sheets or plates 24, which may be formed of sheet metal or any other suitable material, to provide a closed casing. Access is had to one side of the casing, at one side of the bed, by a door 25, hinged at 26, and which may be held closed by gravity or by any suitable means.

Mounted to move vertically within the casing 21 is a plug support 27, in the form of a rectangular frame, of angle iron or the like. This frame is adapted to be moved into the upper frame 22 to assume a position flush with the upper surface thereof and to be moved to a position adjacent to the lower frame 23, so access may be had thereto by opening the door 25. The frame 23 carries a plug spring bottom 28, similar to the spring bottom 14, which is attached to the same. Rigidly attached to the opposite ends of the frame 27 are brackets 29, Figure 6. These brackets are generally L-shaped and their vertical arms are adapted to extend within the frame 27 and carry horizontal extensions 30, attached to the horizontal web of the angle iron frame 27, by rivets 31 or the like. The horizontal arms 32 of the brackets 29 have elongated vertical sleeves 33, rigidly secured thereto, and these sleeves have a sliding fit upon vertical guide rods 34. The vertical guide rods 34 are disposed at the opposite ends of the upper and lower frames 22 and 23, at points equi-distantly spaced from the opposite sides thereof and are rigidly attached to the frames 22 and 23, as shown at 35. The function of the rods 34 and brackets 29 and elongated sleeves 33 is to guide the plug frame 27 in its vertical movement and prevent any perceptible tilting action of the same. The opposite end sheets 24 are provided with elongated slots 36, through which the horizontal arms 32 of the brackets project.

Means are provided to raise and lower the brackets 29, comprising endless sprocket chains 37, arranged exteriorly of and adjacent to the opposite ends of the casing 21. These sprocket chains engage about upper and lower sprocket wheels 38 and 39, carried by stub shafts 40, suitably attached to the end sheets 24. The sprocket wheels 38 and 39 are disposed in vertically aligned pairs, adjacent to the slots 36, affording vertical runs of the sprocket chains which are attached to knuckles 41, Figure 6, by pintles 42. The knuckles 41 are rigidly attached to the horizontal arms of the brackets. The sprocket chains extend laterally and outwardly from their vertical runs and toward one side of the bed and pass about the sprocket wheels 43, rigidly at-

tached to a horizontal longitudinal shaft 44. The shaft 44 is journalled in bearings 45, which are rigidly attached to the casing 21. The shaft 44 extends near and parallel with one side of the bed and is equipped at one end with a worm wheel 46 and this worm wheel engages and is driven by a worm 47, formed upon a transverse shaft 48. This shaft is journalled in bearings 49, rigidly attached to the casing 21. The shaft 48 10 extends to and slightly beyond the side of the bed remote from the shaft 44 and is equipped at its free end with a crank 50, by means of which it may be turned.

In applying the device or attachment to the bed, a suitable number of links 15 in the intermediate portion 19 of the spring bottom are removed, to provide a rectangular opening, and the hooks at the ends of the links adjacent to this opening are engaged within apertures 51, formed 20 in the horizontal web of the upper frame 22. The frame 22 has its sides arranged parallel with the side of the bed, whereby the shaft 48 extends transversely of the bed, as explained. The casing 21 is entirely and bodily supported by and 25 from the spring bottom 14 and the lower end of the casing is spaced from the floor so that it does not contact therewith at any time. This eliminates the use of the usual complicated structure for attachment to the frame of the bed or 30 the frame of the spring bottom, and permits of the casing 21 being permanently yieldingly supported by the spring bottom, thereby increasing the comfort of the bed, in use.

The numeral 52 designates a mattress arranged 35 upon the spring bottom 14 in the usual manner. This mattress is provided in its portion over the intermediate section 19 of the spring bottom, with an opening 53, for receiving a mattress plug 54, which rests upon the vertically movable plug frame 27, and may be attached thereto for movement therewith, if desired. The mattress plug 54, when in the uppermost position, has its upper surface flush with the upper surface of the mattress 52 and therefore forms a continuation of 45 the mattress.

The operation of the bed is as follows:

With the plug frame 27 in the uppermost position, the mattress plug 54 forms, in effect, a continuation of the mattress 52, and the bed may 50 be used in the ordinary manner. The presence of the plug and the means to raise and lower it, does not interfere with the angular adjustment of the head and foot sections 18 and 20 of the spring bottom. When it is desired that the patient use 55 a bed pan or the like, the crank 50 is turned in a direction to cause the sprocket chains 31 to move the brackets 29 downwardly. The downward movement of these brackets moves the plug frame 27 downwardly, in turn lowering the mattress plug 54. When the plug frame and mattress plug 60 are moved to the lowermost position opposite the door 25, this door is opened, and the bed pan placed upon the plug frame 27. The crank 50 is now turned in a direction to raise the plug frame 65 27, which will elevate the bed pan and bring the

same into a suitable position for use by the patient. The crank 50 is again turned to lower the bed pan so that it may be removed by opening the door 25 subsequently to which the mattress plug 54 is again placed upon the plug frame 27, 5 and this plug frame is again returned to the uppermost position, the mattress plug 54 entering the opening in the mattress and assuming its normal position.

It is to be understood that the form of my 10 invention herewith shown and described is to be taken as a preferred example of the same, and that various changes in the size, shape, and arrangement of parts may be resorted to without departing from the spirit of my invention or the 15 scope of the subjoined claim.

Having thus described my invention, I claim:

A bed comprising a spring bottom for supporting a mattress having an opening formed therein, the spring bottom having an opening to be arranged adjacent to the opening in the mattress, the opening in the spring bottom being spaced a considerable distance from the sides and ends of the spring bottom, a vertical casing attached to and suspended from the spring bottom at the 25 opening therein and entirely supported by the spring bottom to partake of the yielding action of the spring bottom, said casing having its opposite sides also spaced a considerable distance from the sides of the spring bottom, said casing 30 having its opposite ends provided with longitudinal slots, a plug frame mounted within the casing to be moved vertically, vertical guide rods mounted within the casing and rigidly secured thereto and disposed adjacent to the slots and 35 arranged between the plug frame and the ends of the casing, brackets rigidly attached to the opposite portions of the plug frame and having guide sleeves slidably mounted upon the vertical rods, said brackets also extending through the 40 slots to the outer sides of the ends, upper and lower spaced sprocket wheels mounted upon the outer side of each end of the casing adjacent to the ends of the slot, a sprocket chain mounted adjacent to each end of the casing and engaging 45 the upper and lower sprocket wheels to provide a vertical run which is attached to the adjacent bracket between the sprocket wheels, both sprocket chains extending laterally from the upper and lower sprocket wheels to and beyond 50 the same side of the casing, a horizontal shaft disposed outwardly of and mounted upon the last named side of the casing and arranged close to the casing, sprocket wheels mounted upon the horizontal shaft and engaging the sprocket 55 chains, a worm wheel mounted upon the horizontal shaft, a transverse shaft mounted upon the casing and having a worm to engage the worm wheel, and an element accessible from one side of the spring bottom to turn the transverse 60 shaft, the arrangement being such that the horizontal shaft, sprocket wheels carried thereby, and worm wheel are disposed inwardly of the spring bottom and covered by the spring bottom.
